(57) **CLAIM**

The ornamental design for a foldable laundry hamper, as shown and described.

DESCRIPTION

FIG. 1 is a perspective view of a foldable laundry hamper, in an open state;

FIG. 2 is a front view of the foldable laundry hamper of FIG. 1;

FIG. 3 is a top view of the foldable laundry hamper of FIG. 1;

FIG. 4 is a left side view of the foldable laundry hamper of FIG. 1, wherein the right side view is the same as the left side of view;

FIG. 5 is a perspective view of the foldable laundry hamper of FIG. 1, wherein the laundry bags are de-attached from the supporting frame;

FIG. 6 is a perspective view of the foldable laundry hamper of FIG. 1, wherein one of the laundry bags is removed away from the supporting frame;

FIG. 7 is a front view of the supporting frame of the foldable laundry hamper in FIG. 6, wherein the front view is the same as the back view;

FIG. 8 is a top view of the supporting frame of the foldable laundry hamper in FIG. 6;

FIG. 9 is a left side view of the supporting frame of the foldable laundry hamper of FIG. 6, wherein the left side view is the same as the right side of view;

FIG. 10 is a perspective view of the supporting frame of the foldable laundry hamper of FIG. 6, when the supporting frame is in its collapsed state;

FIG. 11 is a front view of the supporting frame of the foldable laundry hamper in its collapsed state of FIG. 6, wherein the front view is the same as the back view; and, FIG. 12 is a top view of the supporting frame of the foldable laundry hamper of FIG. 6 in its collapsed state.
